UNITED STATES PATENT OFFICE.

HIRAM S. LASHER, OF BRONX, NEW YORK, ASSIGNOR TO UNDERWOOD ELLIOTT FISHER COMPANY, OF NEW YORK, N. Y., A CORPORATION OF DELAWARE.

TYPEWRITING MACHINE.

Application filed November 7, 1925. Serial No. 67,544

This invention relates to a fan-fold web-typing machine of the well-known Underwood type. In said machine a longitudinally folded web is interleaved with short carbons, 5 and is fed around the platen of the machine to be typed upon, the platen being elevated at intervals to strip the carbons.

It has been customary to split the folds of the web during the carbon-shifting operation by means of knives mounted on the carbon-carrying blades. Since there is a great 10 length of split web between the platen and the splitting blades, it is difficult to keep the printed forms on the plies of the web in 15 proper registration in some cases.

In this invention, novel means are provided whereby the web will be split by means of an independent splitting device, which may be mounted on a carbon-carrier on a forward 20 extension thereof, so that the web will be conducted in unsplit condition up to a point considerably nearer the platen of the machine. Said splitting means may comprise a plurality of knives having cutting edges at an 25 angle, said knives being laterally adjustable, so as to accommodate different widths of web. The knives may be rockable upon studs to facilitate the individual threading of the knives between the plies of the web.

30 Other features and advantages will hereinafter appear.

In the accompanying drawings,

Figure 1 is a cross-sectional view in elevation through the center of an Underwood fan-fold typewriting machine, having the invention applied thereto, and shows the web in typing position.

Figure 2 is a plan view of the same machine as illustrated in Figure 1.

40 Figure 3 is a diagrammatic view, and shows the platen in its elevated position, the web being straightened out for the carbon-shifting operation.

Figure 4 is a cross-sectional view in elevation through the supports for the web-splitting knives.

According to the method of handling the work in this invention, a fan-fold web 10 is drawn up from a supply at the rear of the 50 machine, and passed over a supporting member 11, the plies 12 of the web being interleaved with carbons 13 which are supported at the rear thereof by means of carbon-blades 14. The plies of the web are also interleaved 55 with splitting or slitting knives 15, which are

rockably mounted on supporting studs 16, adjustably mounted on cross-rails 17.

The leading edges of the carbons and of the web are aligned so as to form a pack, which is inserted downwardly over a table 19 and under a platen 20, and is fed therearound by means of feed-rolls 21. The platen is then rotated to position the web past the printing point and over a front table 22, as shown in Figure 1, so that the first form may be typed 60 upon by means of type-bars 23.

After completely typing the first form, the platen is elevated, as shown in Figure 3, and the leading edge of the web is drawn forwardly to a gage 25, the carbon-carrier being 65 then moved rearwardly, so as to present the carbons to a fresh form of the web.

After stripping the carbons, the platen is again lowered to its normal position, and the first form is torn off against a knife 26. Other 70 forms are treated in a similar manner. In order to facilitate the elevation of the platen, the same is mounted on a platen-axle 27 journaled in end plates 28 of a platen-frame. Said platen-frame is rockably mounted on a 75 fixed shaft 29, and is locked in its normal position against a cross-bar 38 by means of a 80 clamping member, not shown.

The knives 15 are rockably mounted upon the studs 16, which have square heads 30 at 85 the bottom thereof, designed for sliding engagement with cross-rails 17. The rails are secured to a plate 31 which carries also, fast thereto, a pair of blocks 32 upon which the carbon-blades 14 are detachably mounted.

In order that the splitting knives may be individually threaded between the plies of the web, and in order to facilitate their lateral adjustment to conform with webs of different widths, novel means including finger-screws 90 18 are provided to secure the knives upon an angular block or support 33 and for simultaneously securing the block to the rails 17. The knives 15 are provided with heels 34 designed to engage with plates 35 upwardly extending from the block 33, so as to hold the knives at a predetermined angle, as shown 95 in Figure 2.

The Underwood machine is provided with 100 means for quickly removing the web and its associated carbons. To this end, the plate 31 is detachably mounted on a truck-plate 36, which is arranged to reciprocate towards and away from the platen. The plate 31 has pins 37 fitting into holes in the truck-plate, the 105 110

pins having slots designed to engage with locking members 39 which are pivotally mounted on the truck-plate at 40. The truck-plate 36 is mounted on wheels 41 which engage with rails 42, the wheels themselves being mounted on secondary plates 43, which are secured to the truck-plate by means of screws, as detachable units.

The web is laterally guided between side gages 44 adjustably mounted on the supporting member 11, and also by means of gages or guides 45 adjustably mounted on the blocks 32 of the carbon-carrier. The carbon-carrier is limited in its rearward travel by means of a stop-gage 46 settable mounted on one of the rails 42, the carbon-carrier being stopped by the gage when the same is moved rearwardly by means of a handle 47 secured to the plate 31.

20 Variations may be resorted to within the scope of the invention, and portions of the improvements may be used without others.

Having thus described my invention, I claim:

25 1. The combination with a typewriting machine having a platen, means for conducting a longitudinally fan-folded web to the platen, and means for displacing a plurality of carbons interleaved with the plies of the web, said last-mentioned means including a carrier having a plate and means for attaching the carbons to said plate, of means for separating the plies of the web, said last-mentioned means being adjustably mounted upon said plate, at a point between the means for attaching the carbons and the platen.

30 2. The combination with a typewriting machine having a platen, means for conducting a web having a plurality of longitudinally fan-folded plies to the platen, and means for controlling the position of carbons interleaved with the plies of the web, of means for separating the plies of the web before insertion around the platen, said last-mentioned means including a series of blades having cutting edges, the blades being interleaved with the plies of the web and being effective to sever the plies at the folds thereof, said blades being mounted to reciprocate with the means for controlling the position of the carbons between the carbon-blades and the platen.

35 3. The combination with a typewriting machine having a carbon-carrier arranged to reciprocate towards and away from a revoluble platen around which a web having a plurality of fan-folded plies is passed, the plies being interleaved with carbons attached to the carbon-carrier, of means for splitting the plies of the web, said means including knives adjustably mounted on the carbon-carrier, at a point between the anchoring point of said carbons and the platen.

40 4. In a carbon-carrier for a typewriting machine of the fan-fold type, having means

for holding and shifting a plurality of carbons, and means for splitting the plies of a fan-folded web, said last-mentioned means including a plurality of knives arranged upon the carbon-carrier so as to split the plies during the carbon-shifting operation, said knives being mounted upon the carbon-carrier at a point between the carbon-holding means and the platen of the machine.

45 5. In a typewriting machine, the combination with a carriage and a platen, of means for directing a fan-folded web toward the platen, a carbon-sheet-holding device arranged to be reciprocated on said carriage, said device including bars extending from opposite sides between the folds of the web to which the ends of the carbons are secured, and means for splitting the plies of the web, said last-mentioned means including a plurality of knives mounted upon said device at a point between the bars and the platen.

50 6. In a typewriting machine, the combination with a carriage and a platen, of a carbon-sheet-holding device arranged to be reciprocated on said carriage, said device including carbon-carrying bars extending from opposite sides between the folds of a fan-fold web, fold-slitters carried by said device, between the latter and the platen, and side-edge guides also carried by said device for directing the web to the bars and to the fold-slitters.

55 7. In a typewriting machine, the combination with a carriage and a platen, of means for directing a fan-folded web toward the platen, a carbon-sheet-holding device arranged to be reciprocated on said carriage, said device including bars extending from opposite sides between the folds of the web to which the ends of the carbons are secured, and means carried by said device, for splitting the plies of the web, said last-mentioned means including knives arranged to interleave with the plies of the web, said knives being rockably mounted upon studs to facilitate the individual threading of the knives between the plies, supports upon which the studs are mounted, and cross-rails carried by said device, the supports being adjustably secured to the cross-rails.

60 8. In a typewriting machine, the combination with a carriage and a platen, of means for directing a fan-folded web toward the platen, a carbon-sheet-holding device arranged to be reciprocated on said carriage, said device including bars extending from opposite sides between the folds of the web to which the ends of the carbons are secured, means for splitting the plies of the web, said last-mentioned means including knives arranged to interleave with the plies of the web, said knives being rockably mounted upon studs to facilitate the individual threading of the knives between the plies, the studs being adjustably mounted upon said carbon-sheet-holding device, and means for simultaneously locking the knives

and the studs upon which the knives are rockably mounted.

9. In a fan-fold typewriting machine, the combination with a platen and a carbon-carrier, of fold-slitters at the front of the carbon-carrier, and a movable truck upon which the carbon-carrier and the fold-slitters are mounted.

10. In a fan-fold typewriting machine, the combination with a platen and a carbon-carrier, movable to strip the carbons of fold-slitters traveling with the carbon-carrier and engaging the web-folds between said platen and said carbon-carrier.

15. 11. In a fan-fold typewriting machine, the combination with a platen and a carbon-carrier movable to strip the carbons, of fold-slitters traveling with the carbon-carrier and engaging the web-folds between said platen and 20 said carbon-carrier, and a stop limiting the carbon-stripping travel of said carbon-carrier and the stroke of said fold-slitters.

12. In a fan-fold typewriting machine, the combination with a platen and a carbon-carrier movable to strip the carbons, of fold-slitters traveling with the carbon-carrier and engaging the web-folds between said platen and said carbon-carrier, a stop limiting the carbon-stripping travel of said carbon-carrier 30 and the stroke of said fold-slitters, and side-edge guides for the web.

13. The combination with a typewriting machine having a platen, means for guiding a longitudinally fan-folded web to said platen, 35 a carbon carrier for shifting the position of carbons interleaved with the plies of said web, and means for elevating the platen during the carbon-shifting operation, of means at the front of the carbon carrier for slitting the

plies of the web previously to the insertion of 40 the web around the platen, said last-mentioned means being connected to move with the carbon-carrier.

14. The combination with a typewriting machine having a platen, a platen-frame 45 therefor, means for elevating said platen by rocking said platen-frame, and a web-course at the introductory side of the platen for conducting a longitudinally fan-folded web, having a plurality of plies, to the platen, said 50 course having rails for guiding a carbon-carrier arranged to reciprocate upon said rails, of means for slitting the plies of the web at the folds thereof, said carbon-carrier and last-mentioned means including a truck arranged 55 to reciprocate upon said rails for carrying them, said truck including a plate, wheels under said plate to facilitate the sliding of the truck, knives on said truck interleaved with the plies of the web, said knives being 60 rockably mounted on studs, the studs being mounted on cross-rails fast to the plate, and means for simultaneously locking all the knives in either effective or ineffective position, said last-mentioned means being also 65 effective to lock the studs on which the knives are rockably mounted to said cross-rails.

15. In a fan-fold typewriting machine, a carbon-carrier movable to shift the carbons 70 while interleaved between the plies of a fan-fold web, carbon-holding means on said carbon-carrier, and a plurality of knives arranged upon the carbon-carrier at a point between the carbon-holding means and the platen so as to slit the plies during the carbon-shifting operation. 75
